UNITED STATES PATENT OFFICE.

GILBERT H. PRINDLE, OF PHILADELPHIA, PENNSYLVANIA.

DESIGN FOR BOAS.

Specification forming part of Design No. 6,793, dated August 5, 1873; application filed July 25, 1873.

To all whom it may concern:

Be it known that I, GILBERT H. PRINDLE, of Philadelphia, in the county of Philadelphia, and in the State of Pennsylvania, have invented certain new and useful Designs for Boas; and do hereby declare that the following is a full, clear, and exact description thereof, reference being had to the accompanying drawing making a part of this specification, in which is shown a section of my improved boa.

The distinctive feature of my design consists in a row or series of balls, A, formed upon or of one continuous roving, which ends in

a tassel, B, and having upon each side a series of loops, C, arranged as shown.

What I claim as new, and as my invention, is—

The design for a boa, substantially as shown. In testimony that I claim the foregoing I have hereunto set my hand this 12th day of July, 1873.

GILBERT H. PRINDLE.
